UNITED STATES PATENT OFFICE.

JOHN W. DILLEY AND JOHN F. COOK, OF DALLAS, TEXAS.

STREET AND STATION INDICATOR.

1,233,201.

Specification of Letters Patent. Patented July 10, 1917.

Application filed August 1, 1916. Serial No. 112,520.

To all whom it may concern:

Be it known that we, JOHN W. DILLEY and JOHN F. COOK, citizens of the United States, and residents of Dallas, in the county 5 of Dallas and State of Texas, have invented a new and Improved Street and Station Indicator, of which the following is a full, clear, and exact description.

This invention relates to a device which 10 is adapted to be displayed in a car at a point plainly in view of the passengers for the purpose of announcing or exhibiting the names of stations or street crossings along an electric or steam railway as the car or 15 train approaches the stations or crossings, and also for exhibiting the names of business firms or advertising data.

The invention has for its general objects 20 to improve and simplify the construction and operation of apparatus of this character so as to be reliable and efficient in use, comparatively simple and inexpensive to manufacture and keep in operative condition and have its various instrumentalities operative 25 from a single pull cord or pushbutton within the control of the conductor or the person in charge of the car or train.

A more specific object of the invention is 30 the provision of a plurality of ribbons and coöperating spools so arranged that portions of the ribbons are displayed through openings in the casing of the device for exhibiting street or station names, firm names, advertising data, etc., the reels being mounted 35 and operated in a novel manner so that they will move step by step by the operation of a single actuating means.

Another object of the invention is to provide a simple and effective reversing device 40 for the reels to permit the ribbons to be driven in either direction.

Still another object of the invention is to 45 so mount the reels of a name-bearing ribbon that they can be bodily reversed to display either side of the ribbon through the opening in the casing.

With such objects in view, and others which will appear as the description proceeds, the invention comprises various novel 50 features of construction and arrangement of parts which will be set forth with particularity in the following description and claims appended hereto.

In the accompanying drawings, which 55 illustrate one embodiment of the invention and wherein similar characters of reference

indicate corresponding parts in all the views,

Figure 1 is a vertical section of the machine taken on the line 1—1, Fig. 4;

Fig. 2 is a view of the right-hand side of the machine with portions broken away and the doors removed;

Fig. 3 is a sectional view on the line 3—3, Fig. 1, looking forwardly into the machine;

Fig. 4 is a vertical section on the line 4—4, Fig. 1, and looking rearwardly into the machine;

Fig. 5 is a detail view of the ratchet device for the upper conveyer or ribbon and the ribbon stop mechanism;

Fig. 6 is a perspective view of one of the members of the stop mechanism;

Fig. 7 is a perspective view of one of the members of the stop mechanism for the lower ribbon;

Fig. 8 is a detail view of one of the members of the stop mechanism for the upper ribbon or conveyer;

Fig. 9 is a plan view of the part shown in Fig. 8.

Fig. 10 is a fragmentary view of the upper ribbon or conveyer for the advertising cards;

Fig. 11 is a fragmentary view of the station or street crossing bearing ribbon;

Fig. 12 is a front view of the machine drawn on a small scale;

Fig. 13 is a plan view of the attaching device on the end of the pull rope.

Fig. 14 is a perspective view of certain of the parts for supporting one of the lower reels; and

Figs. 15 and 16 are detail sectional views respectively on the lines 15—15 and 16—16, Figs. 2 and 1.

The indicator is adapted to be removably mounted on a suitable bracket at the forward end of a car, and when the car reaches the end of a trip and is to return without the car being turned, the device is removed and placed at the other end of the car. A pull cord extends through the car and either end of the pull cord is adapted to be operatively connected to the device. If the device is to be electrically operated, a push-button will be arranged at each end of the car or at any other suitable point, and the device will have means for connection with the push-button circuit, as will be readily understood.

The indicating device comprises a casing A having openings 1 and 2 in its front for

respectively displaying advertising data, names of business firms and the like, and street or station names, the openings being covered by glass 3 for protection.

5 Behind the opening 1 and within the casing is a flexible strip, ribbon or conveyer B which winds and unwinds on reels C and C'. The conveyer B has longitudinal slits 4 adjacent its side edges for receiving 10 tongues 5 on the ends of advertising or display cards 6, as shown in Fig. 10. By this means the advertising data can be changed whenever desired. Adjacent the side edges of the conveyer B are apertures 7 for co- 15 operating with stop or registering means which insures stoppage of the conveyer with an advertising card directly behind or in register with the opening 1 of the casing. The apertures 7 lie centrally of each advertising card 6.

Behind the lower opening 2 lies a flexible element or ribbon D which winds and unwinds on reels E and E'. The ribbon D bears the names of street crossings or stations, the space reserved for each name being indicated by the broken line rectangles 8 in Fig. 11. Along the edges of the ribbon D are apertures 9 coöperating with stop or registering devices in the casing for insuring the proper register of the station or street names with the opening 2 in the casing. The ribbon D may have station or street names on both sides, but the names on one side are reversely arranged with respect to the names on the other side.

25 Mounted within the casing at the rear thereof is a horizontal main shaft 10 from which power is derived for actuating the ribbons B and D intermittently or step by step. This shaft 10 is actuated electrically or mechanically. For the former purpose a solenoid 11 is arranged within the casing and the core 12 is connected by a rod 13 with the arm 14 of the bell-crank lever 15, such lever being fastened to the shaft 10 and having an arm 16 which is operatively connected with the ratchet devices for the ribbon feeding means. The solenoid operates the bell-crank lever 15 in one direction and a spring 17 connected with the lever moves the same in the opposite direction. It will be understood that pushbuttons will be arranged at opposite ends of the car and suitable means employed to connect the 35 pushbutton circuit with the solenoid of the device when the latter is changed from one end of the car to the other. To mechanically operate the shaft 10 the latter has one end extending out of the casing, and fastened to this extending end is an arm 18 formed with a crotched extremity 19 into which is fitted a spool-like knob 20, as shown in Fig. 13. The conductor's pull rope 21 has one of these members 20 fastened to each end so that the indicating and

advertising device can be mounted at either end of the car, it being merely necessary to insert one member 20 or the other in the crotch of the crank 18. The crotch has a spring catch 22 for holding the member 20 releasably in place. 70

The upper reels C and C' are mounted on tubular shafts 23 and 24, respectively. These shafts are supported at one end in fixed bearings 25, as shown in Fig. 4, and the opposite ends of the shafts are supported on bearing pins 26 which are carried by a door 27 at the side of the casing opposite from the bearings 25. By opening the door the adjacent ends of the reels are left unsupported and the reels can be removed from the shafts. The reels C and C' are provided with intermeshing gear wheels 28 and 29 so that the reels can be rotated, causing the ribbon or conveyer B to wind on one reel and unwind from the other. The gear 29 has a gear 30 connected therewith which meshes with a large gear 31. This gear wheel 31 is connected by a sleeve 32 with a ratchet wheel 33 journaled on the shaft or stud 34 suitably mounted in the frame or 85 in the casing. Coöperating with the ratchet wheel is a pawl 35 fulcrumed at 36 on a rocker 37 loosely journaled on the shaft 34, and this rocker is connected at 38 by a link 39 with the arm 16 of the bell-crank lever 15. A spring 40 interposed between the rocker and tail end of the pawl serves to engage the toothed end 41 of the pawl with the ratchet wheel 33. When the pawl moves in a clockwise direction, Fig. 1, the toothed end slips idly over the ratchet wheel, but when the pawl moves with the rocker in the opposite direction, the pawl imparts a partial turn to the ratchet wheel, so that the 90 reels are actuated through the train of gears 31, 30, 29 and 28. Only one reel is positively driven at a time, and for this purpose the reels are adapted to be clutched to the respective gear wheels 28 and 29 by 95 the left heads h of the reels being frictionally held against the adjacent gear wheels 28 and 29. In Fig. 4 it will be noted that the lower reel is frictionally clutched to the gear wheel 29, while the upper reel is free 100 from its gear wheel 28. This relation is maintained while the ribbon moves intermittently in one direction throughout its length, and when the ribbon is to be reversed, the lower reel will be unclutched from its gear 105 29 and the upper reel clutched to its gear 28. For maintaining this relation a toothed wheel 42 is journaled on a stud 43' carried by the door 27, as clearly shown in Figs. 2 and 4, and this wheel has five teeth so arranged that one tooth 43 engages the hub on the right end, Fig. 4, of either reel. The hub of the lower reel C' is shown engaged by the toothed wheel 42, and consequently 110 this wheel maintains the lower reel clutched 115 to its gear 29. The upper reel is clutched to its gear 28 by the toothed wheel 42, and consequently 120 this wheel maintains the upper reel clutched to its gear 28. For maintaining this relation a toothed wheel 42 is journaled on a stud 43' carried by the door 27, as clearly shown in Figs. 2 and 4, and this wheel has five teeth so arranged that one tooth 43 engages the hub on the right end, Fig. 4, of either reel. The hub of the lower reel C' is shown engaged by the toothed wheel 42, and consequently 125 this wheel maintains the lower reel clutched to its gear 29. For maintaining this relation a toothed wheel 42 is journaled on a stud 43' carried by the door 27, as clearly shown in Figs. 2 and 4, and this wheel has five teeth so arranged that one tooth 43 engages the hub on the right end, Fig. 4, of either reel. The hub of the lower reel C' is shown engaged by the toothed wheel 42, and consequently 130 this wheel maintains the lower reel clutched to its gear 29.

to its gear 29. When the wheel 42 is moved a distance equal to one tooth the said wheel will engage the upper reel and disengage the lower reel and thereby cause the advertising ribbon to travel in a reverse direction. 5 This wheel 42 is moved only when the end of the ribbon is reached, and to effect this the wheel 42 has ten crown teeth 44 with which co-operates a reciprocatory push rod 10 45, Fig. 2, which has its upper end resting in a fork 46 of an oscillatory arm or lever 47, while the lower end of the push rod is connected at 48 with a crank arm 49 on the main shaft 10. A spring 50 is connected 15 with the push rod 45 to assist in holding the latter down or seated in the part 46 of the lever 47. The rod 45 reciprocates with each step by step movement of the ribbon, but the upper end of the push rod does not 20 engage with any tooth 44 except when the lever 47 is held in lowered position, as when the end of the ribbon is reached, and consequently, when the next reciprocation of the rod 45 takes place it will engage a tooth 44 25 and move the wheel 42 one step. The manner in which the lever 47 will be held lowered will be presently described in connection with the registering mechanism for the ribbon B. The ribbon B passes upwardly from the upper reel C over an idler roller 51, and from this roller the ribbon passes downwardly behind the upper opening 1 in the casing, under a lower idler roller 52, and thence to the reel C'. Behind the 30 portion of the ribbon B lying between the guide rollers 51 and 52 is a backing plate 53, and through this project stop pins 54 which are adapted to engage in the apertures 7 in the edge of the ribbon B, for the 35 purpose of registering the advertising cards of the ribbon with the opening 1 of the casing. These pins 54 are carried on the front ends of the members 55, which are hingedly connected at 56 with arms 57 carried by a 40 horizontal shaft 58. This shaft 58 is rocked with every movement of the ratchet device, so that the pins 54 will be removed to allow the ribbon to travel a step forward, and when the end of the forward step is reached, 45 the stop pins 54 will engage in the next apertures 7 and cause the ribbon B to stop at the proper point. The rock shaft 58 is rocked during the forward or idle movement of the pawl 35, so that the pins 54 will be 50 retracted from the rod before the pawl actuates the ratchet wheel and causes the ribbon to move. To do this one of the arms 57 on the shaft 58 has an arm or member 59 extending downwardly toward the ratchet 55 wheel, as shown in Figs. 1 and 5, and the lower end of this arm 59 lies in the path of a cam 60 connected with or carried by the rocker 37, so that during the movement of the rocker in a clockwise direction, Fig. 5, 60 the cam 60 will strike the arm 59 and move

the arms 57 to the left, Fig. 5, so as to retract the stop pins 54.

During the first half of the movement of the rocker 37 no effect is produced except the movement of the ratchet pawl 35, and during the second half of the movement the cam 60 engages the member 59 and retracts the stop pins 54 from the ribbon B. These pins are held retracted as long as the cam 60 is in engagement with the member 59. 75 During the first half of the return movement of the rocker the pawl 35 moves the ratchet wheel and the cam wipes under the member 59, still holding the same outwardly and the pins 54 retracted, but at the beginning of the second half of the return movement the cam moves from under the member 59, so that the stop pins 54 can move forwardly and bear against the rear side of the ribbon B, and when the next openings 7 reach the pins 54 the latter spring into the openings and stop the ribbon. This forward movement of the pins into the openings 7 causes a shoulder 61 on the member 59 to engage the tail end of the pawl 90 to disengage the toothed end 41 from the ratchet wheel, so that the actuating means for the ribbon is stopped at the same time the pins 54 enter the openings 7 of the ribbon. The forward movement of the pin-carrying members 55 is effected by a helical spring 62 coiled around the shaft 58 and fastened thereto at 63, Fig. 3, the other end 64 of the spring being fastened to the adjacent bearing 66 for the shaft 58. 95

At each end of the ribbon B there is an opening 7 only at one edge, and consequently one of the stop pins 54 will bear against the rear side of the ribbon and will be prevented thereby from moving forwardly with the other pin 54. This restraining movement is made use of to hold the arm 47 lowered in order that the push rod 45 will move the reversing or switching wheel 42 one step forward to unclutch the clutched reel for the upper ribbon and clutch the unclutched reel to the driving means. The hub 67 of the arm 47 is connected with the shaft 58 by a lost motion connection consisting of a slot 68 and pins 115 69. This lost motion connection allows the shaft 58 to rock under the tension of the spring 62 for engaging one stop pin 54 in the alining opening of the ribbon while the other stop pin bears against the back of the ribbon. The hub 67 is connected by a helical spring 70 with the shaft 58, so that normally the shaft 58 operates through the spring 70 to move forwardly the locking pin 54, which is connected with the hub 120 67 of the arm 47. In Fig. 3 the left arm 57 is connected with the shaft 58 through the spring 70, and the right arm 57 is positively connected with the shaft 58, it being understood that the stop pin 54 con- 130

nected with the left arm 53 is the one that is held back by the unperforated end portions of the ribbon when the ribbon is unwound, and being thus held back the locking pin 54 causes the reels to be reversed, as heretofore explained.

Taking up the lower ribbon D, it will be noted that the ribbon passes from the upper reel forwardly to and in front of a support F in the form of a plate which lies behind the forward opening 2, and the ribbon passes backwardly from under the support F to the lower reel E. The reels E and E' are supported respectively on hollow shafts 71 and 72 which are carried at the right ends, Fig. 3, on a hanger 73, and the opposite or left ends of the shafts, Fig. 3, are supported on bearing pins 74 which are disposed in sleeves 75. These sleeves are 15 slidable in openings 76 in the upper and lower ends of a hanger 73', and each sleeve has a U-shaped extension 77 slidably engaging in keyways 78 in the openings 76, as clearly shown in Figs. 4 and 14. By 20 this arrangement the sleeves can slide in the bearing openings 76, and on the centering pins 75. The extensions 77 extend completely through the hanger 73' and are adapted to be engaged by suitable means, 25 whereby one sleeve 75 is forced axially against the head 79 of the associated reel, so that such reel will have its opposite head 80 pressed into frictional engagement with a clutch disk 81. The clutch disks 81 for 30 the upper and lower reels are connected respectively with gear wheels 82 and 83 which mesh with an intermediate gear wheel 84 that is driven by means of a ratchet device from the bell-crank lever 15. 35 As shown in Figs. 2 and 4, a bowed spring 85 is slidably mounted in a guideway 86 of a frame 87, which frame is connected by hinges 88 with one side of the casing so as to swing inwardly and outwardly through 40 an opening 89, such opening being normally closed by a door 90 which is shown in section, Fig. 15, and broken away in Fig. 2. This spring slides vertically and has a knob 91 projecting outwardly through 45 the door, so that the spring can be moved up or down. The upper and lower extremities of the spring are adapted to bear against either one of the extensions 77 of the clutch sleeves 75. In Fig. 4 the spring 50 shows the upper reel clutched to its gear 82, while the lower reel is free and disengaged from its gear 83.

The lower ribbon is actuated from the shaft 10, which latter has its arm 16 connected by a link 92 with a rocker 93 journaled on a suitable bearing member or shaft 94, and pivoted at 95 on this rocker is a pawl 96 similar in arrangement and function to the pawl 35. The pawl cooperates with a

ratchet wheel 97 which is connected by a sleeve 98 with the intermediate gear wheel 84. As the pawl moves in a clockwise direction, Fig. 1, it has no effect on the ratchet wheel but on the reverse movement the spring 98' of the pawl throws the tooth 99 thereof into engagement with the ratchet wheel so as to move the latter in an anti-clockwise direction and thereby feed the lower ribbon D one step forward to thereby bring the next station or street name into view. The return movement of the rocker and pawl, together with the ratchet wheel, is effected by the spring 17, which is connected with the bell-crank lever 15. The stopping of the ribbon at the proper time is effected by stop pins 100 carried on and extending rearwardly from the lower ends of depending arms 101 carried by a horizontal shaft 102. Fastened to this shaft 102 is an arm 103, Fig. 1, which extends rearwardly and normally lies in the path of a cam 104 associated with the rocker 93 and serving to perform a similar function as the cam 60 so that the locking pins will be retracted from the ribbon D before the ratchet mechanism 90 actuates the latter, and a spring 105 is connected with the arm 103 so as to cause the stop pins 100 to move rearwardly to engage in the openings of the ribbon D and thereby arrest the ribbon when a name is in registry with the lower opening 2 of the casing. This lever 103 has a shoulder 106 which engages the pawl at the time the stop pins enter the openings of the ribbon D, and consequently the pawl will be released from the 100 ratchet wheel at the proper instant.

The lower reels and ribbon are so mounted that the position of the reels can be reversed, that is to say, the reel E can be moved downwardly and the lower reel E' 105 can be moved upwardly so as to bring the rear side of the ribbon to the front. This is especially useful where the car travels on a belt line and the ribbon will have the names of the streets or stations on both 110 sides but in reverse order. For this purpose the hangers 73 and 73' are mounted to rotate on their centers. The hanger 73' is operatively connected with a wing nut or equivalent device 106, Fig. 3, which is located outside the casing so that, by turning the nut though one hundred and eighty degrees, the position of the reels E and E' will be reversed. Normally the hangers engage 115 spring catches 107 located in the casing and arranged to engage the lower ends of the hangers, as clearly shown in Figs. 3 and 4. Before the ribbon and reels can be thus reversed it is necessary to remove the ribbon support F. This support is mounted on the forward ends 108 of elbow levers 109, which have their lower extremities 110 fastened to a horizontal shaft 111 journaled in

bearings 112 in the bottom of the casing. One end of the shaft is provided with a wing nut or equivalent means 113, whereby the shaft can be turned to throw the levers 109 and the support F from the full to the dotted-line position, Fig. 2. Spring-pressed balls 114 in the bearings 112 engage the shaft 111 to yieldingly hold the levers 109 in their full-line position, Fig. 2. The support F is connected by pivots 114 to the levers 109, and a spring 115 connects the support F with each of the levers in such a manner as to cause the support to swing on its pivots as the levers move backwardly. This swinging movement of the support is limited by a pin 116, Fig. 2, on the support and engageable with the adjacent lever 109. Normally the support is disposed in a vertical plane, and when it moves rearwardly the spring 115 comes into play and tends to move the support F to lie more nearly in the plane of the forwardly-extending members of the levers 109, so that the support when moving rearwardly will take up less space and pass between the reels E and E'. When the support is in its rearmost position the reels can be readily reversed without the support interfering.

Whenever it is desired to remove the lower reels and ribbon the support F is moved to the rear part of the casing, as just explained, and the door 90 is opened so that the reels will be accessible and can be pulled longitudinally off their respective shafts. As the door 90 is opened the frame 87 is swung outwardly to thereby disengage the centering pins 74 and sleeve 75 from the reels. This leaves the reels free to be removed from their shafts.

If it is desired to move the ribbon backwardly, the cord 21 is first pulled and held so as to disengage the stop pins 100 from the ribbon D, and then a knob or winged nut 115 is actuated to turn the intermediate gear 84, such knob 115 being disposed outside of the casing and connected with this gear through a shaft 116 which extends through a hollow shaft 94.

From the foregoing description taken in connection with the accompanying drawings, the advantages of the construction and method of operation will be readily understood by those skilled in the art to which the invention appertains, and while we have described the principle of operation, together with the machine which we now consider to be the best embodiment thereof, we desire to have it understood that the machine shown is merely illustrative and that such changes may be made when desired as fall within the scope of the appended claims.

Having thus described our invention, we claim as new and desire to secure by Letters Patent:

1. In a device of the class described, the combination of an oscillatory carrier, a pawl thereon, a ratchet wheel engageable with the pawl, a gearing receiving motion from the ratchet wheel, a ribbon, reels for the ribbon and operatively connected with the gearing, whereby the ribbons move step by step from the ratchet wheel, said ribbons having apertures, stops engageable in the apertures to control the movement of the ribbon, a member connected with the stops and normally engaging the pawl to hold the same released from the ratchet wheel, means movable with the carrier to engage said member and retract the stops from the ribbon while the pawl moves on its idle stroke, and arranged to release the member during the active stroke of the pawl, whereby the stops will engage the ribbon before the next openings reach the stops, so that the latter will spring into the openings and cause the member to release the pawl from the ratchet wheel.

2. A device of the class described comprising a casing having a display opening, a ribbon having portions containing matter to be displayed and having apertures along its edges at each of said portions, means for moving the ribbon, stops arranged to enter the apertures to cause successive portions of the ribbon to register with the opening in the casing, means for actuating the stops into and out of engagement with the ribbon, and a reversing mechanism for changing the direction of movement of the ribbon, and means for controlling the said mechanism by one of the stops.

3. A device of the class described comprising a casing having an opening, a ribbon traveling past the opening, reels to which the ends of the ribbon are attached, supporting hangers for the reels, a support behind the opening and over which the ribbon passes, means for moving the support away from the opening and between the reels, and means for moving the hangers to reverse the position of the reels and thereby expose the opposite side of the ribbon through the opening.

4. A device of the class described comprising a casing having an opening, a ribbon traveling past the opening, reels to which the ends of the ribbon are attached, supporting hangers for the reels, a support behind the opening and over which the ribbon passes, means for moving the support away from the opening and between the reels, means for moving the hangers to reverse the position of the reels and thereby expose the opposite side of the ribbon through the opening, and an intermittent mechanism operatively connected with the reels when the hangers are in either operative position.

5. A device of the class described comprising a casing having a view opening, a ribbon movable past the opening, reels for

the ribbon, hangers supporting the reels, means for turning the hangers to reverse the position of the reels, a gear for each reel, an intermediate gear meshing with the reel gears and located in the center around which the hangers swing, and a step-by-step mechanism for actuating the intermediate gear.

- 5 6. A device of the class described comprising a casing having a view opening, a ribbon movable past the opening, reels for the ribbon, hangers supporting the reels, means for turning the hangers to reverse the position of the reels, a gear for each reel, an intermediate gear meshing with the reel gears and located in the center around which the hangers swing, a step-by-step mechanism for actuating the intermediate gear, and means connected with the intermediate gear for turning the same by hand while

- 10 20 7. An apparatus of the class described comprising a casing having a view opening, a ribbon movable past the opening, reels for the ribbon, hangers in which the reels are mounted, a gear wheel associated with each reel, a spring mounted in the casing and arranged to engage one reel at a time for holding such reel clutched to its gear wheel, means outside the casing for operating the spring to reverse the direction of travel of the ribbon, and intermittent mechanism for operating the gear wheels.

- 15 30 8. A device of the class described including a pair of reels, a ribbon having its ends connected with the reels, shafts for the reels, a hanger in which the shafts are mounted, another hanger, centering pins in the last-mentioned hanger for engaging the reels, sleeves slidable on the centering pins and in the last-mentioned hanger, gears associated with the reels, a device engaging one sleeve or the other for clutching one reel to its associated gear at a time while leaving the other reel free, and driving means applying motion to the gears intermittently.

- 40 45 9. A device of the class described including a pair of reels, a ribbon having its ends connected with the reels, shafts for the reels, a hanger in which the shafts are mounted, another hanger, centering pins in the last-

55 mentioned hanger for engaging the reels, sleeves slidable on the centering pins and in the last-mentioned hanger, gears associated with the reels, a device engaging one sleeve or the other for clutching one reel to its associated gear at a time while leaving the other reel free, driving means applying motion to the gears intermittently, and means for turning the hangers to shift the position of the reels for exposing either side 60 of the ribbon to view.

65 10. A device of the class described comprising a ribbon, reels on which the ribbon winds and unwinds, a reversible supporting means for the reels, a support over which the ribbon travels, levers on which the support is mounted, and means for moving the levers and the support away from the ribbon and between the reels, whereby the reels may be reversed.

70 11. A device of the class described comprising a ribbon, reels on which the ribbon winds and unwinds, a reversible supporting means for the reels, a support over which the ribbon travels, levers on which the support is mounted, means for moving the levers and the support away from the ribbon and between the reels, whereby the reels may be reversed, and means for holding the levers in a position with the support engaged with the ribbon.

75 12. A device of the class described comprising a ribbon, reels on which the ribbon winds and unwinds, a reversible supporting means for the reels, a support over which the ribbon travels, levers on which the support is mounted, means for moving the levers and the support away from the ribbon and between the reels, whereby the reels may be reversed, an intermittent mechanism for 80 driving one of the reels at a time, and a stop pin movable automatically into and out of engagement with the ribbon to arrest the motion thereof and throw out the intermittent mechanism.
